United States Patent Office

Des. 225,643
Patented Dec. 26, 1972

225,643

REACTION TESTING DEVICE

Larry Harrison, Clifton Springs, N.Y., assignor to
Xerox Corporation, Stamford, Conn.

Filed May 19, 1971, Ser. No. 144,937

Term of patent 14 years

Int. Cl. D19—07

U.S. Cl. D25—1

Fig. 3.

Fig. 4.

Fig. 5.

Fig. 6.

Fig. 7.

FIG. 1 is a rear perspective view of the reaction testing device showing my new design;

FIG. 2 is a front perspective view of the reaction testing device;

FIG. 3 is a top plan view of the reaction testing device;

FIG. 4 is a front elevational view of the reaction testing device;

FIG. 5 is a rear elevational view of the reaction testing device;

FIG. 6 is a side view of the reaction testing device; and,

FIG. 7 is another side view of the reaction testing device.

I claim:

The ornamental design of a reaction testing device, substantially as shown.
